TOOTHBRUSH

Tom W. Sherrod and Niles J. G. Edwards, Jackson, Miss.

Application February 1, 1951, Serial No. 14,075

Term of patent 14 years

(Cl. D9—2)

To all whom it may concern:

Be it known that we, Tom W. Sherrod and Niles J. G. Edwards, citizens of the United States and both residents of Jackson, State of Mississippi, whose post-office addresses are, respectively, 812 Fairview Street and 950 North Street, have invented a new, original, and ornamental Design for a Toothbrush, of which the following is a specification, reference being had to the accompanying drawing, forming a part hereof.

Fig. 1 is a perspective view of a toothbrush, showing my new design;

Fig. 2 is a plan view of the same;

Fig. 3 is a side elevational view; and

Fig. 4 is a view in front elevation.

We claim:

The ornamental design for a toothbrush, substantially as shown.

TOM W. SHERROD.
